RAILWAY TRAFFIC CONTROLLING APPARATUS

Harry C. Vantassel, Swissvale, Pa., assignor to
The Union Switch & Signal Company, Swiss-
vale, Pa., a corporation of Pennsylvania

Application September 9, 1939, Serial No. 294,177

8 Claims. (Cl. 246—161)

My invention relates to railway traffic controlling apparatus, and particularly to apparatus of the type involving a railway switch and a signal governing traffic movements over the switch. More specifically, my invention relates to the release of approach and stick locking for a switch.

One feature of my invention is the provision of novel and improved means for preventing a reduction in the release period for approach or stick locking, if a time element device which determines that release period has not fully returned to its normal condition after it has been previously energized.

15 The apparatus of my invention is an improvement over that disclosed in the copending applications Serial No. 323,286, filed December 3, 1928, by Lester E. Spray for Multiple control apparatus; and Serial No. 416,061, filed December 20 23, 1929, by Howard A. Thompson for Multiple control apparatus.

I shall describe one form of apparatus embodying my invention, and shall then point out the novel features thereof in claims.

25 The accompanying drawing is a diagrammatic view showing one form of apparatus embodying my invention.

Referring to the drawing, the reference characters 3 and 3a designate the track rails of a stretch of main railway track divided by insulated joints 5 to form a main section 1T and an approach section AT. Each track section is provided with a track circuit including a track battery 6, connected across the rails adjacent one end of the section, and a track relay designated by the reference character R preceded by the reference character for the associated section, connected across the rails adjacent the opposite end of the section.

40 A track switch 1 is included in section 1T for connecting the main track with an auxiliary track X. Switch 1 is provided with an operating mechanism M which, as here shown, is controlled by a polarized switch control relay WR.

45 Traffic moving toward the left as shown in the drawing, which I shall assume is the west-bound direction, is governed by a signal 2A for the main track, and by a signal 2D for the auxiliary track X. Eastbound traffic on the main track is governed by a signal 4. Only a portion of the operating circuit is shown for each of the signals 2A and 4. A portion of the energizing circuit for a signal control relay 2AHR is also shown, controlled by track relay 1TR and by a lever V which may be located at some suitable

control point, such for example as an interlocking tower. A second signal control relay 4AHR may be controlled similarly to relay 2AHR. As shown in the drawing, the signals are of the semaphore type, but may be of any other suitable design.

The contacts operated by the various relays and other devices are identified by numbers, each such number having a distinguishing prefix from which it is separated by a dash when the associated contact is shown apart from the relay or other device by which it is operated. The prefix for each of these contact numbers comprises the reference character for the relay or other device by which the associated contact is operated. For example, contact 2AS—24, shown in the operating circuit for signal 2A, is identified by the number 24 which is separated by a dash from the prefix 2AS which is the reference character for relay 2AS by which this contact is operated. 10 Similarly, contact TE—32, shown in a pick-up circuit for, and adjacent to, the winding of the stick relay TES, is identified by the number 32 which is separated by a dash from the prefix TE which is the reference character for a time element device TE by which this contact is operated. 15

An approach and stick locking relay associated with signal 2 and designated by the reference character 2AS controls, in part, the switch control relay WR by means of a front contact 2AS—18, 20 so that relay WR cannot be energized for effecting operation of switch 1 unless relay 2AS is energized. Only one portion of the normal and reverse control circuits for relay WR is shown in the drawing, and the portions of these circuits which are not shown may be controlled in any suitable manner, such for example as by a lever operated by a leverman in an interlocking tower. 25

40 Energization of relay 2AS is controlled in part by time element means here shown as a thermal device TE, by a first slow release auxiliary stick relay TES, and by a second auxiliary stick relay RP.

45 Time element means or device TE operates a first time contact TE—12 which is normally closed, and which opens in response to energization of device TE, and which is slow to close when device TE becomes deenergized. Device TE also operates a second, normally open, contact TE—32 which is slow to close when device TE becomes energized. 50

A second approach and stick locking relay, designated by the reference character 4AS, is associated with signal 4, and may be controlled sim- 55

ilarly to relay 2AS, and hence its control circuits are omitted from the drawing.

Contact 26, shown in the operating circuit for signal 2A, is operated in conjunction with switch 1, and is closed only when switch 1 occupies the normal position.

Contacts 1 and 8, shown in the circuits for relay RP, are operated in conjunction with signals 2A and 2D, respectively, and are closed when the corresponding signals indicate stop, and become opened when the arms of the corresponding signals leave the stop position.

Having described, in general, the arrangement and control of the apparatus shown in the accompanying drawing, I shall now describe, in detail, its operation.

As shown in the drawing, all parts are in the normal condition, that is, switch 1 is in its normal position; lever V is in its normal position, in which contact 21 is open; signals 2A, 2D and 4 are indicating stop; switch control relay WR is energized by current of normal polarity; track relays 1TR and ATR are energized; approach and stick locking relays 2AS and 4AS are energized; second auxiliary stick relay RP is energized; and relays 2AHR, 4AHR and TES, and time element device TE are deenergized.

Both a pick-up and a stick circuit are shown closed for second auxiliary stick relay RP, the pick-up circuit passing from terminal B of a suitable source of current, not shown in the drawing, through contacts 7 and 8 of signals 2A and 2D, respectively, back point of contact TES-11, contact TE-12, back point of contact TES-13, and the winding of relay RP to terminal C of the same source of current. The stick circuit for this relay passes from terminal B, through contacts 7 and 8 of signals 2A and 2D, respectively, contact 14 of relay RP, and the winding of relay RP to terminal C.

Both a pick-up and a stick circuit are also closed for approach locking relay 2AS, the pick-up circuit for this relay passing from terminal B, through contact RP-9, contact 10 of relay 2AHR, contact 15 of relay ATR, and the winding of relay 2AS to terminal C. The stick circuit for this relay passes from terminal B, through contact RP-9, contact 10 of relay 2AHR, front point of contact 17 of relay 2AS, and the winding of relay 2AS to terminal C.

I shall assume that the leverman desires to arrange for a westbound train to move over the main track, with switch 1 in its normal position. As shown in the drawing, switch 1 is already in its normal position, and the leverman has therefore only to initiate the clearing of signal 2A by moving lever V to its *r* position. If the other contacts not shown in the drawing in the control circuit for relay 2AHR are also closed, this operation of lever V completes the circuit for relay 2AHR including contact 21 of lever V closed in the right-hand or *r* position, and contact 22 of relay 1TR.

Relay 2AHR, upon becoming energized, opens its contact 10 in the circuits previously traced for relay 2AS, causing this relay to become deenergized.

With relay 2AHR energized and relay 2AS deenergized and other contacts in the operating circuit for signal 2A closed, this operating circuit is now completed, including contact 23 of relay 4AS, contact 2AS-24, contact 25 of relay 2AHR, contact 26 of switch 1, and the mechanism of signal 2A to terminal C. The arm of signal 2A therefore moves away from its stop

position to a position for directing traffic movements to enter section 1T, thereby opening its contact 7 in the pick-up and stick circuits traced for the second auxiliary stick relay RP, and thus causing this relay to also become deenergized.

If now the westbound train moves through section AT and enters section 1T, relay 1TR will become deenergized, opening its contact 22 and thus causing relay 2AHR to become deenergized, which in turn causes the arm of signal 2A to return to the stop position.

With relays 2AHR and 1TR deenergized, a second pick-up circuit is completed for relay 2AS, this circuit passing from terminal B, through contact RP-9, contact 10 of relay 2AHR, contact 16 of relay 1TR, and the winding of relay 2AS to terminal C. With relay 2AS energized, the approach locking for switch 1 is released by the closing of contact 2AS-18 in the circuit for relay WR, but this relay remains deenergized while the train occupies section 1T, due to its control by relay 1TR, which however is not shown in the drawing.

I shall now assume that the leverman again clears signal 2A for a westbound train to proceed on the main track over switch 1 in its normal position, and that after the train enters section AT but before it enters section 1T, the leverman returns the arm of signal 2A to the stop position by returning lever V to its normal position and thereby opening contact 21 and deenergizing relay 2AHR. With the arm of signal 2A returned to the stop position, the pick-up circuit previously traced for relay RP will become closed. Relay 2AS will, however, remain deenergized on account of its first pick-up circuit being open at contact 15 of relay ATR because of the presence of the train on section AT, and its second pick-up circuit being open at contact 16 of relay 1TR, because the train has not entered section 1T.

An energizing circuit will therefore be completed for time element device TE, passing from terminal B, through contact 29 of relay RP, contact 30 of relay 2AS, contact 31 of relay TES, and time element device TE to terminal C. Time element device TE will now open its contact TE-12 in the pick-up circuit previously traced for relay RP which will, however, remain energized by its stick circuit also previously traced.

Contact TE-32, which is slow in picking up, completes a pick-up circuit for relay TES upon the lapse of a first delay period of time, this circuit passing from terminal B, through contact RP-9, contact 10 of relay 2AHR, back point of contact 17 of relay 2AS, contact TE-32, and the winding of relay TES to terminal C. Relay TES, upon becoming energized, closes its contact 33, thereby completing a stick circuit which is the same as the pick-up circuit previously traced for this relay except including contact 33 instead of contact TE-32. With relay TES energized, the energizing circuit traced for time element device TE is opened at contact 31 of relay TES.

Contact TE-12, which is slow to close when time element device TE becomes deenergized, will complete a third pick-up circuit for relay 2AS after the lapse of a second delay period of time, this circuit passing from terminal B, through contact RP-9, contact 10 of relay 2AHR, front point of contact TE-11, contact TE-12, front point of contact TE-13, and the winding of relay 2AS to terminal C.

It follows that under the procedure just out-

lined, the locking release period is the time required for the third pick-up circuit for relay 2AS to become closed after the leverman deenergizes relay 2AHR, causing the arm of signal 2A to return to the stop position, and includes a first delay period of time comprising the pick-up time for device TE, and a second delay period of time comprising the closing period for contact TE-12 when device TE becomes deenergized.

I shall next assume that all parts of the apparatus are again returned to the normal condition, and that the leverman, as before, clears signal 2A for a westbound traffic movement on the main track over switch 1 in the normal position. I shall further assume that the leverman then returns the arm of signal 2A to the stop position after a train enters section AT but before the train enters section IT, and thereby starts the operation of time element device TE. I shall also further assume that the leverman then again clears the arm of signal 2A, and that, a second time, before the train passes this signal, he returns the arm of signal 2A to the stop position.

I shall also assume that time element device TE is in some other condition than its normal condition, when the leverman returns the arm of signal 2A to the stop position the second time, because of the signal having been returned to stop before. Contact TE-12 will therefore be open, and relay RP cannot become energized. Contact 29 of relay RP will therefore be open, and hence time element device TE will not at once become energized when the leverman returns the arm of signal 2A to stop the second time. With time element device TE deenergized, this device will now return to its normal condition, causing its contact TE-12 to close and thereby complete the pick-up circuit traced for relay RP. With relay RP then energized, time element device TE will become energized, causing relay TES to become energized and relay 2AS to become energized after time element device TE has again returned to the normal position permitting its contact TE-12 to close.

Therefore, the approach locking release period, when the leverman returns the arm of signal 2A to the stop position and then again clears this signal and almost immediately again returns the arm of signal 2A to the stop position, includes part of the usual closing period for contact TE-12 of device TE, in addition to the usual approach locking release period which includes the first time delay period required for time element device TE to attain its operated control condition upon becoming energized and the second delay period required for time element device TE to return to the normal condition when time element device TE becomes deenergized.

From the foregoing description and the accompanying drawing, it follows that in apparatus embodying my invention, I have provided approach locking release means including a time element device requiring a first delay period for attaining a release control condition when the time element device becomes energized, and requiring a second delay period to return to the normal condition when the time element device becomes deenergized, and that I have also provided novel and improved means for preventing release of the approach locking in less than a period of time comprising the first and second delay periods, if the time element device is in a condition other than its normal condition when the release of the approach locking is initiated.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track including a switch, a signal for governing traffic movements over said switch, an approach locking relay, a first slow release auxiliary stick relay having a first and a second contact each of which is provided with a front and a back point, a second auxiliary stick relay, a time element device having a first time contact which is slow to close when said time element device becomes energized and having a second time contact which opens when said time element device becomes energized and which is slow to close when said time element device becomes deenergized, a signal relay, a pick-up circuit for said approach locking relay controlled by a front contact of said second auxiliary stick relay and by a back contact of said signal relay and including said second time contact and the front points of said first and second contacts of said first auxiliary stick relay, a stick circuit for said approach locking relay controlled by a front and a back contact of said second auxiliary stick relay and said signal relay respectively, a pick-up circuit for said second auxiliary stick relay including said second time contact and the back points of said first and second contacts of said first auxiliary stick relay and closed only when said signal indicates stop, a stick circuit for said second auxiliary stick relay closed only when said signal indicates stop, a pick-up circuit for said first auxiliary stick relay controlled by said first time contact and by a front contact of said second auxiliary stick relay and also by back contacts of said signal and approach locking relays, a stick circuit for said first auxiliary stick relay controlled by a back contact of said approach locking relay, a circuit controlled by a front contact of said second auxiliary stick relay and by back contacts of said approach locking and first auxiliary stick relays for energizing said time element device, manually controllable means for energizing said signal relay, a circuit including a front contact of said signal relay for controlling said signal, and means controlled by a front contact of said approach locking relay for controlling said switch.

2. In combination, a stretch of railway track including a switch, a signal for governing traffic movements over said switch, an approach locking relay, a first slow release auxiliary stick relay having a first and a second contact each of which is provided with a front and a back point, a second auxiliary stick relay, a time element device having a first time contact which is slow to close when said time element device becomes energized and having a second time contact which opens when said time element device becomes energized and which is slow to close when said time element device becomes deenergized, a pick-up circuit for said approach locking relay controlled by a front contact of said second auxiliary stick relay and including said second time contact and the front points of said first and second contacts of said first auxiliary stick relay, a stick circuit for said approach locking relay controlled by a front contact of said second auxiliary stick relay and a pick-up circuit for said signal relay.

ond auxiliary stick relay including said second time contact and the back points of said first and second contacts of said first auxiliary stick relay and closed only when said signal indicates stop, a stick circuit for said second auxiliary stick relay closed when said signal indicates stop, a pick-up circuit for said first auxiliary stick relay controlled by said first time contact and by a front contact of said second auxiliary stick relay and also by a back contact of said approach locking relay, a stick circuit for said first auxiliary stick relay controlled by a back contact of said approach locking relay, a circuit controlled by a front contact of said second auxiliary stick relay and by back contacts of said approach locking and first auxiliary stick relays for energizing said time element device, manually controllable means for clearing said signal, and means controlled by a front contact of said approach locking relay for controlling operation of said switch.

3. In combination, a stretch of railway track including a switch, a signal for governing traffic movements over said switch, an approach locking relay, a first auxiliary stick relay, a second auxiliary stick relay, a time element device having a first time contact which is slow to close when said time element device becomes energized and having a second time contact which opens when said time element device becomes energized and which is slow to close when said time element device becomes deenergized, means controlled by said second time contact and by said first and second auxiliary stick relays in the energized condition for energizing said approach locking relay, a stick circuit for said approach locking relay controlled by a front contact of said second auxiliary stick relay, means controlled by said second time contact and by said first auxiliary stick relay in the deenergized condition for energizing said second auxiliary stick relay if said signal is controlled to indicate stop, a stick circuit for said second auxiliary stick relay closed when said signal is controlled to indicate stop, a pick-up circuit for said first auxiliary stick relay controlled by said first time contact and by a back contact of said approach locking relay and also by a front contact of said second auxiliary stick relay, a stick circuit for said first auxiliary stick relay controlled by a front contact of said second auxiliary stick relay and by a back contact of said approach locking relay, means controlled by a front contact of said second auxiliary stick relay and by back contacts of said approach locking and first auxiliary stick relays for energizing said time element device, means for clearing said signal, and means controlled by a front contact of said approach locking relay for controlling operation of said switch.

60. 4. In combination, a stretch of railway track, a signal for governing traffic movements into said stretch, a second traffic governing device for said stretch, an approach locking relay, a first auxiliary stick relay, a second auxiliary stick relay, a time element device which upon becoming energized requires the lapse of a first delay period of time to attain a given energized control condition and which upon then becoming deenergized requires a further delay period of time to attain its normal condition, means controlled by said time element device in its normal condition and by said first and second auxiliary stick relays in the energized condition for energizing said approach locking relay, a stick circuit for said approach locking relay controlled by a front contact

of said second auxiliary stick relay, means controlled by said time element device in its normal condition and by said first auxiliary stick relay in the deenergized condition for energizing said second auxiliary stick relay if said signal indicates stop, a stick circuit for retaining said second auxiliary stick relay in the energized condition if said signal indicates stop, a pick-up circuit for said first auxiliary stick relay controlled by said time element device in said given energized control condition and by a front contact of said second auxiliary stick relay and also by a back contact of said approach locking relay, a stick circuit for said first auxiliary stick relay controlled by a front contact of said second auxiliary stick relay and by a back contact of said approach locking relay, means controlled by a front contact of said second auxiliary stick relay and by back contacts of said approach locking and first auxiliary stick relays for energizing said time element device, means for clearing said signal, and means controlled by a front contact of said approach locking relay for controlling said second traffic governing device.

5. In combination, a stretch of railway track, a signal for governing traffic movements into said stretch, a second traffic governing device for said stretch, an approach locking relay, a first auxiliary stick relay, a second auxiliary stick relay, a time element device which upon becoming energized requires the lapse of a first delay period of time to attain a given energized control condition and which upon then becoming deenergized requires a further delay period of time to attain its normal condition, a pick-up circuit for said approach locking relay controlled by said time element device in its normal condition and by said first auxiliary stick relay in the energized condition, a stick circuit for said approach locking relay controlled by a front contact of said second auxiliary stick relay, a pick-up circuit for said second auxiliary stick relay controlled by said time element device in its normal condition and by said first auxiliary stick relay in the deenergized condition, a stick circuit for retaining said second auxiliary stick relay in the energized condition if said signal indicates stop, a pick-up circuit for said first auxiliary stick relay controlled by said time element device in said given energized control condition, a stick circuit for said first auxiliary stick relay controlled by a front contact of said second auxiliary stick relay and by a back contact of said approach locking relay, means controlled by a front contact of said second auxiliary stick relay and by back contacts of said approach locking and first auxiliary stick relays for energizing said time element device, means for clearing said signal, and means controlled by a front contact of said approach locking relay for controlling operation of said second traffic governing device.

6. In combination, a stretch of railway track, a signal for governing traffic movements on said stretch, a second traffic governing device for said stretch, an approach locking relay, an auxiliary stick relay, a time element device which upon becoming energized requires the lapse of a first delay period of time to attain a given energized control condition and which upon then becoming deenergized requires the lapse of a further delay period of time to return to its normal condition, means controlled by said time element device in the normal condition for energizing said auxiliary stick relay, a stick circuit for then retaining said stick relay in the energized condition if said sig-

nal indicates stop, means controlled by said time element device upon attaining its said energized control condition and then returning to its normal condition for energizing said approach locking relay, a stick circuit for said approach locking relay controlled by a front contact of said auxiliary stick relay, means controlled by a front contact of said auxiliary stick relay and by a back contact of said approach locking relay for energizing said time element device, means for clearing said signal, and means controlled by a front contact of said approach locking relay for controlling operation of said second traffic governing device.

5 7. In combination, a stretch of railway track, a signal for governing traffic movements on said stretch, a second traffic governing device for said stretch, an approach locking relay, an auxiliary stick relay, a time element device which upon becoming energized requires the lapse of a first delay period of time to attain a given energized control condition and which upon then becoming deenergized requires the lapse of a further delay period of time to return to its normal condition,

10 20 means controlled by said time element device in the normal condition for energizing said auxiliary stick relay, a stick circuit for then retaining said stick relay in the energized condition if said signal indicates stop, means controlled by said time element device upon attaining its said energized control condition and then returning to its normal condition for energizing said approach locking relay, a signal relay, means for energizing said signal relay, a stick circuit for said approach locking relay controlled by a front contact of said auxiliary stick relay and by a back contact of said auxiliary stick relay and by a front contact of said approach locking relay for energizing

said time element device, means controlled by a back contact of said approach locking relay and by a front contact of said signal relay for clearing said signal, and means controlled by a front contact of said approach locking relay for controlling operation of said second traffic governing device.

5 8. In combination, a stretch of railway track, a signal for governing traffic movements on said stretch, a second traffic governing device for said stretch, approach locking means, a time element device which upon becoming energized requires the lapse of a first delay period of time to attain a given reverse control condition and which upon then becoming deenergized requires the lapse of a second delay period of time to return to its normal condition, means for clearing said signal and for returning it to the stop condition, a stick relay, a normal and a reverse contact closed by said time element device in its normal and reverse control conditions respectively, a pick-up circuit for said stick relay controlled by said normal contact, a stick circuit for retaining said stick relay in the energized condition while said signal indicates stop, means controlled by said reverse contact for transferring said normal contact from the pick-up circuit for said stick relay to an energizing circuit for said approach locking means, means controlled by said stick relay and by said approach locking means for energizing said time element device when said stick relay is energized and said approach locking means is deenergized, and means controlled by said approach locking means for preventing operation of said second traffic governing device until said approach locking means becomes energized after said signal is returned to the stop condition.

HARRY C. VANTASSEL.
